STORAGE BOX FOR RAZOR BLADES
AND COUNTER THEREFOR

Andrew Balint, 1572 3rd Ave.,
New York, N.Y. 10028

Filed Sept. 1, 1965, Ser. No. 86,790

Term of patent 14 years

(Cl. D58—13)

FIG. 1

FIG. 2

FIG. 3

FIG. 4

FIG. 5

FIG. 6

FIG. 1 is a perspective view of a storage box for razor blades and counter therefor showing my new design, the view being of the top, front, and a side thereof;

FIG. 2 is a front end view;

FIG. 3 is a rear end view;

FIG. 4 is a side elevational view thereof;

FIG. 5 is a top plan view thereof; and

FIG. 6 is another side elevational view thereof.

The dominant features of the design reside in the full line portions of the drawing.

I claim:

The ornamental design for a storage box for razor blades and counter therefor, substantially as shown and described.
